INVENTOR.

Alexander Holub

BY
Alexander Holub
his ATTORNEY

UNITED STATES PATENT OFFICE.

ALEXANDER HOLUB, OF NEW YORK, N. Y.

WRENCH.

1,322,240.

Specification of Letters Patent.

Patented Nov. 18, 1919.

Application filed May 20, 1919. Serial No. 298,396.

To all whom it may concern:

Be it known that I, ALEXANDER HOLUB, a citizen of Hungary, residing at New York city, in the county of New York and State 5 of New York, have invented new and useful Improvements in Wrenches, of which the following is a specification.

This invention relates to wrenches, and the same has for its principal object the 10 provision of a simple and efficient wrench, embodying features of construction, which permit it to be adjusted instantly to fit nuts of any ordinary dimension, and which include means whereby, when fitted to a nut, 15 it can be locked unyieldingly in the fitted position.

With the foregoing and other objects in view, the invention resides in the details of construction and in the arrangement and 20 combination of parts hereinafter described, more particularly set forth in the annexed claims, and illustrated in the accompanying drawings forming a material part of this specification.

25 In the accompanying drawings:—

Figure 1 is a side elevational view of my improved wrench.

Fig. 2 is a rear elevational view of the same.

30 Fig. 3 shows a longitudinal section, taken on the line 3—3 of Fig. 1.

Fig. 4 shows a cross-section, taken on the line 4—4 of Fig. 1.

Referring in detail to the drawings, the 35 numeral 5 denotes a stem, made preferably of rectangular-shape in cross-section, and with an integral head or jaw 6. Cut transversely in one side of the stem, a short distance back of the head as shown, is a toothed 40 region 7, the teeth having pitch or inclination toward the head, and being cut so that their points lie flush with the surface plane of the stem. In Fig. 4, it will be clearly seen that the teeth 7 do not traverse the 45 stem from edge to edge, but are cut intermediate its width, so as to permit the provision at the extremities of the teeth, along the opposite edges of the stem, of longitudinal recesses 8, the purpose of which will 50 presently appear.

Through the thickness of the stem, midway its width, is provided an elongated slot 9, whose defining walls are flat and parallel, it being noted that this slot at the rear 55 end merges into a circular eye 10.

Slidably mounted on the stem is a sleeve

11 having an integral head or jaw 12, representing a counterpart of the head or jaw 6. The sleeve 11, on the side adjacent the toothed region 7, is provided with a square opening 13, within which is loosely fitted a square plate 14, having teeth 15 adapted to coöperate with the teeth 7, and having also at the extremities of its teeth, recesses 16 confronting and paralleling the stem recesses 8. Seated longitudinally in the recesses 8 and 16 are bowed springs 17, arranged as best shown in Fig. 3, with their bowed portions resting in the plate recesses, and with their extremities resting in the 70 stem recesses and capable of sliding therein under flexure. The springs 17 tend normally to hold the plate spaced from the stem so that the teeth of the former are held out of engagement with the teeth of the latter. 75

Traversing the stem slot 9 and snugly fitting the flat defining walls thereof, is the square shank 18 of a screw, the head 19 of which is countersunk in the plate 14 as shown. The shank 18 merges into a threaded 80 end 20, which projects through a circular opening 21 provided in the sleeve 11. The walls of the opening 21 rise exteriorly of the sleeve to produce confronting projections or cam-like portions 22 and 23 which 85 are beveled in opposite directions as illustrated in Fig. 2. Loosely fitting in the circular opening 21 and screw-threaded upon the end 20 of the screw is the integral circular head 24 of a locking lever 25, which 90 beyond the said circular head, has an integral extension 26. This arrangement is such that when the lever is advanced upon the cam portions, the plate teeth will be drawn into the stem teeth, as illustrated 95 in Fig. 2; and, conversely, when the lever is moved into a position to lie between the cam portions, the springs 17 will be permitted to act, causing the plate teeth to be disengaged from the stem teeth, as illustrated in Figs. 3 and 4.

As the wrench is intended to be fitted to nuts of any ordinary dimensions, whatever their specific size, it is necessary, in view of the provision of the coöperating teeth, to 105 grind off or taper the nut engaging faces 27 of the jaws, as shown in Fig. 1, the degree of grinding or tapering being, of course, proportionate to the pitch of the coöperating teeth.

To indicate when the teeth are securely in mesh so as to prevent any relative yield-

ing of the sleeve in respect to the stem, I provide the sleeve with a projecting pin 28, against which the lever may abut. When for any purpose, for instance, for the 5 adjustment or replacement of any of the parts, it is desired to rotate the screw, this may be accomplished by moving the sleeve against the stop 29, in which position the screw is brought centrally of the eye 10 10 where it may be rotated.

From the foregoing description, taken in connection with the accompanying drawings, it will be manifest that by turning the lever into position between the cam portions, the sleeve may be adjusted on the stem in the position necessary to fit the jaws to the object to be turned; whereupon the lever is moved upon the cam portions and against its post, locking the sleeve in its adjusted position.

Having thus described my invention, what I claim is:—

1. In a tool of the character described, a stem having an integral jaw and provided 25 with a toothed region on one side and an elongated slot in its center, a sleeve having an integral counterjaw slidable upon the stem and provided with openings having communication with said slot, one of said 30 openings being square and coming adjacent the toothed region and the other opening being circular in form, a square plate loosely fitting within the square opening and provided with teeth adapted to mesh 35 with the stem teeth, means acting on said plate and tending normally to hold the plate spaced from the stem with the co-operating teeth out of engagement, a screw countersunk in said plate and having anti- 40 turning movement in said slot and having a threaded portion projecting through said circular opening, and means seated in said circular opening and threaded upon the screw whereby manually to impart longitudinal 45 movement to the screw and to effect the engagement or disengagement of the plate teeth with the stem teeth.

2. In a tool of the character described, a stem having an integral jaw and provided 50 with a toothed region on one side and an elongated slot in its center, a sleeve having an integral counterjaw slidable upon the stem and provided with openings having communication with said slot, one of said

openings being square and coming adjacent the toothed region and the other opening being circular in form, a square plate loosely fitting within the square opening and provided with teeth adapted to mesh with the stem teeth, means acting on said plate and tending normally to hold the same spaced from the stem with the co-operating teeth out of engagement, a screw countersunk in said plate and having anti-turning movement in said slot and having a threaded portion projecting through said circular opening, a lever having a portion seated in said circular opening and threaded on said screw whereby manually to impart longitudinal movement to said screw for causing the engagement or disengagement of the plate teeth with the stem teeth, and beveled object-engaging surfaces on one or both of said jaws to compensate for the pitch of the co-operating screws, when the 75 jaws are fitted to an object to be turned.

3. In a tool of the character described, a stem having an integral jaw and provided with a toothed region on one side and an elongated slot in its center, a sleeve having 80 an integral counterjaw slidable upon the stem and provided with openings having communication with said slot, one of said openings being square and coming adjacent the toothed region and the other opening 85 being circular in form, a square plate loosely fitting within the square opening and provided with teeth adapted to mesh with the stem teeth, resilient means acting on said plate and tending normally to hold the same spaced from the stem with the co-operating teeth out of engagement, a screw countersunk in said plate and having anti-turning movement in said slot and having 90 a threaded portion projecting through said circular opening, a lever having a portion seated in said circular opening and threaded on said screw whereby manually to impart longitudinal movement to said screw 95 for causing the engagement or disengagement of the plate teeth with the stem teeth, a stop against which said lever may abut to indicate when the teeth are in engagement, and a stop for limiting the movement of the sleeve on the stem.

In testimony whereof I have signed my name to this specification.

ALEXANDER HOLUB.
